UNITED STATES PATENT OFFICE.

ABNER JUDSON McGEHEE, OF JACKSON, TENNESSEE.

CAR-COUPING.

SPECIFICATION forming part of Letters Patent No. 376,482, dated January 17, 1888.

Application filed July 29, 1887. Serial No. 245,616. (No model.)

To all whom it may concern:

Be it known that I, ABNER JUDSON McGEHEE, a citizen of the United States, residing at Jackson, in the county of Madison and State of Tennessee, have invented new and useful Improvements in Car-Couplings, of which the following is a specification.

My invention relates to improvements in car-couplings; and it consists in certain novel features, hereinafter described and claimed.

In the accompanying drawings, which fully illustrate my invention, Figure 1 is a perspective view of the end of a car provided with my improved coupling. Fig. 2 is a horizontal section showing two draw-heads coupled together. Fig. 3 is a horizontal section of a single draw-head with the several parts in their uncoupled position. Fig. 4 is a detail perspective view of the draw-bar, and Fig. 5 is a detail perspective view of the draw-bar lock.

Referring to the drawings by letter, A designates the end of a car, and B the draw-head, secured to the under side of the same in the usual or any preferred manner. The draw-head B is provided with the forwardly-projecting tongues C C' at its front ends on opposite sides of its center, the inner face or side of the tongue C' being inclined, as shown. The tongue C is horizontally slotted, and is provided 30 with the shoulder D on the inner face of its outer side wall, which is engaged by a similar shoulder on the draw-bar, as will be herein-after more fully set forth.

E designates the draw-bar, consisting of an L-shaped body having the coupling-arm F and locking-arm G. The draw-bar is secured in the front end of the slotted tongue C by means of a pivot-pin, H, inserted vertically through said tongue and the angle of the draw-bar. The coupling-arm F of the draw-bar projects from the tongue C of the draw-head and in its outer end has a recess and a vertical pin-hole, so that it may be used with the link-and-pin coupler, while the locking-arm G extends 40 backward in the longitudinal horizontal slot in the tongue, and is provided with a shoulder, I, on its outer side edge, which engages against the shoulder D of the tongue when the parts are in their coupled position, as clearly shown. The rear end edge of the draw-bar has a beveled portion, J, and a shoulder, K, which shoul-

der is engaged by a latch, L, pivoted in the rear end of the draw-head, and having its shaft M extended through the side of the same and provided with a crank-handle, N, as shown. 55 This crank-handle N is connected by a chain, O, to an arm, P, mounted on the shaft Q, journaled on the end of the car.

R designates a rod extending to the top of the car, and also connected to the arm P. 60

The operation of my device will, it is thought, be readily understood. When the cars are uncoupled, the coupling-arm of the draw-bar projects forward from the draw-head, as clearly shown in Fig. 3. In this position, if the two 65 draw-heads be brought together, the coupling-arm of the draw-bar in each draw-head will enter the opposing draw-head, and, impinging against the inner inclined face of the tongue C' of the draw-head, will be turned inward, the 70 rear sides of the coupling-arms of the draw-bars mutually engaging, as clearly shown in Fig. 2. As the draw-bars are swung around by contacting with the opposing draw-head, the locking-arm will be swung inward, the 75 beveled rear end of the same passing under the latch L, which falls into engagement with the shoulder K, and the shoulder I of the draw-bar engaging the shoulder D of the draw-head. The coupling will thus be completed and the 80 draw-bars firmly held against uncoupling. To uncouple the cars it is necessary only to turn the shaft M, thus raising the latch L out of engagement with the shoulder K, when the tension on the draw-bars will turn them around, 85 so that the coupling-arms may slip past each other.

It will be observed that the cars are automatically coupled by my device, and can be uncoupled from the top or side of the car without the brakeman going between the cars. 90

The construction of the device is very simple, and when coupled the cars will be securely held against uncoupling.

Having thus described my invention, what I 95 claim, and desire to secure by Letters Patent, is—

1. The combination, with the draw-head having the tongues C C', of the draw-bar pivoted in the tongue C and having its rear edge 100 beveled and provided with the notch K, and the latch L, hung in the rear portion of the

draw-head, in position to engage said notch, and having its shaft extended through the side of the same and provided with means for rotating it, substantially as set forth. 5 2. The combination, with the draw - head having the tongues C C', the tongue C being provided with the vertical shoulder D on its inner side, of the draw - bar pivoted in the tongue C, and having a vertical shoulder, I, engaging against the shoulder D, the rear edge of the draw-bar being beveled and provided with the notch K, and the latch L, hung in the

draw-head in position to engage the notch K, and having its shaft extended through the side of the draw-head and provided with means for rotating the same, substantially as specified.

In testimony that I claim the foregoing as my own I have hereto affixed my signature in the presence of two witnesses.

ABNER JUDSON McGEHEE.
